(57) CLAIM

The ornamental design for a water jet housing, as shown and described.

DESCRIPTION

FIG. 1 is a perspective view of a water jet assembly showing our new design;

FIG. 2 is a top view thereof;

FIG. 3 is a front view thereof;

FIG. 4 is a back view thereof;

FIG. 5 is a left side view thereof;

FIG. 6 is a right side view thereof; and,

FIG. 7 is a bottom view thereof.

The broken line portions of FIGS. 1, 2, and 7 are included to show unclaimed subject matter only and form no part of the claimed design.

1 Claim, 7 Drawing Sheets
